TOY CROSSBOW

Paul W. White, New Haven, Conn., assignor to
Parva Products Company, Chicago, Ill., a cor-
poration of Delaware

Application January 20, 1951, Serial No. 13,891

Term of patent 7 years

(Cl. D34—15)

To all whom it may concern:

Be it known that I, Paul W. White, a citizen of the United States, residing at New Haven, in the county of New Haven and State of Connecticut, have invented a new, original, and ornamental Design for Toy Crossbow, of which the following is a specification, reference being had to the accompanying drawing, forming a part thereof, in which:

Fig. 1 is a perspective view of a toy crossbow, embodying my new design;

Fig. 2 is a side elevational view of the toy crossbow shown in Fig. 1;

Fig. 3 is a fragmentary top plan view of the toy crossbow shown in Figs. 1 and 2 with one end of the bow and string broken away; and

Fig. 4 is a front elevational view thereof.

I claim:

The ornamental design for a toy crossbow, sub-
stantially as shown.

PAUL W. WHITE.
